UNITED STATES PATENT OFFICE.

JOHN D. EARNEY, OF SALT LAKE CITY, UTAH.

TRIPLE-GAP SPARK-PLUG.

1,342,431.

Specification of Letters Patent.

Patented June 8, 1920.

Application filed November 3, 1919. Serial No. 835,544.

To all whom it may concern:

Be it known that I, JOHN D. EARNEY, a citizen of the United States, residing at Salt Lake City, in the county of Salt Lake and State of Utah, have invented certain new and useful Improvements in Triple-Gap Spark-Plugs, of which the following is a specification.

My invention relates to the ignition mechanism for internal combustion engines, and has for its special purpose to provide a triple-gap spark plug whereby the electric spark is lengthened and also much increased in temperature.

These objects I accomplish with the device illustrated in the accompanying drawings in which similar letters and numerals of reference indicate like parts throughout the figures and as described in the specification forming a part of this application and pointed out in the appended claims.

In the drawings in which I have shown a substantial embodiment of my invention Figure 1 is an elevation of the spark plug. Fig. 2 is a longitudinal section of the same.

In a great many spark plugs the insulation, commonly made of porcelain, is weakened by making it too slender or by removing the central portion to such an extent that it is easily broken. Also the commonly used spark plugs provide but one gap within the combustion chamber for the electrodes and the present invention provides for three gaps for the electrode and also a strong insulation, and consists of a core 1, substantially cylindrical in shape, and having two opposed inclined bearing faces *a* and *b*. The end portion 2 which is intended to extend within the combustion chamber of the internal combustion engine is semi-cylindrical in shape and has a groove in its end portion as at 3 within which groove the ground electrode is carried. In the body of said end portion 2 is secured two spaced apart metal posts 5, 5 in alignment with the electrode 6 and the end of said ground electrode 4. Each of said posts 5 is also spaced from the adjacent electrode thus forming three gaps between the electrode 6 and the end of the ground electrode 4. The casing of my spark plug consists of the casing 7 which is externally threaded for screwing into the combustion chamber, and internally threaded at its other end to receive the clamping sleeve nut 8. The said casing member 7 has an inclined shoulder

9 formed therein and between said shoulder 9 and said face *b* of the insulator 1, a packing member 10 is used. The said sleeve nut 8 also has a shoulder 11 formed therein on an incline opposed to that of shoulder 9 and between said shoulder 11 and said face *a* a packing member 12 is used in order that when said sleeve nut is screwed into said casing 7 the insulator will not be injured and will be firmly held by the sleeve nut and casing. The upper end of the electrode 6 is enlarged and threaded and a portion of said enlarged part is engaged within said insulator 1. Jam nuts 13 and 14 are screwed on said electrode 6 to hold the usual electric wire which is not shown.

The electric current in passing from the electrode 6 to the ground electrode 4 will jump three gaps *x*, *x'* and *x''*; and the spark will be intensified due to the resistance. As the spark so produced is longer than the spark of one gap commonly used, and hotter, it will induce better combustion and prevent accumulation of carbon in the combustion chamber.

Having thus described my invention I desire to secure by Letters Patent and claim:

1. A spark plug for internal combustion engines comprising a casing to be screwed into the combustion chamber; an insulating core carried therein and having a portion of one end extended to form a semi-cylindrical support for an electrode; a ground electrode screwed into said casing and bent to partially inclose the extension of said insulating core; a central electrode carried and secured in said insulating core and terminating near the diametrical face of said insulating core; and two spaced apart metal posts interposed between the end of said ground electrode and said central electrode to form three spark gaps within said combustion chamber.

2. A spark plug comprising a casing; an insulating core having a semicylindrical extension formed on one end with a face thereon longitudinally and diametrically disposed and with a recess formed in its end portion; a ground electrode secured in said casing bent to engage in the recess in said core; and metal posts secured in the face portion of said core extension.

In testimony whereof I have affixed my signature.

JOHN D. EARNEY.
